United States Patent

Des. 237,910
Patented Dec. 2, 1975

237,910

HAND LOOM

Nickson R. Brubaker, 2232 Draper Ave. 55113; Peter J. Kreisman, 751 Goodrich Ave. 55105; and James C. Ingebretsen, 1761 Summit Ave. 55105, all of St. Paul, Minn.

Filed Dec. 3, 1973, Ser. No. 421,076

Term of patent 14 years

Int. Cl. D15—06

U.S. Cl. D92—15

Fig. 1

Fig. 2

Fig. 3

Fig. 4Fig. 5Fig. 6FIG. 1 is a top plan view of a hand loom showing our new design;

FIG. 2 is an end plan view of the loom of FIG. 1 as viewed from the bottom of FIG. 1;

FIG. 3 is an end plan view of the loom of FIG. 1 viewed from the end opposite that of FIG. 2;

FIG. 4 is a bottom plan view of the loom of FIG. 1;

FIG. 5 is a side elevational view of the left side of the loom of FIG. 1 with the right side being a mirror image thereof; and

FIG. 6 is a side elevational view of the loom of FIG. 1 with a portion of the ends thereof broken away to show the tooth configuration.

We claim:

The ornamental design for a hand loom, as shown and described.
